US0D1054640S

(12) **United States Design Patent** (10) **Patent No.:** **US D1,054,640 S**
(45) **Date of Patent:** **** Dec. 17, 2024**

(54) **SIDE BRUSH**

- (71) Applicant: **Intelligent Cleaning Equipment Holdings Co. Ltd.**, Tortola (VG)
- (72) Inventors: **Simon Nai Pong Chen**, Dongguan (CN); **Stefano Daniele Abelli**, Piacenza (IT); **Gianfranco Ghirarduzzi**, Piacenza (IT); **Lianhua Yang**, Dongguan (CN)
- (73) Assignee: **Intelligent Cleaning Equipment Holdings Co. Ltd.**, Tortola (VG)
- (**) Term: **15 Years**
- (21) Appl. No.: **29/865,186**
- (22) Filed: **Jul. 13, 2022**

Related U.S. Application Data

CLAIM

The ornamental design for a side brush, as shown and described.

DESCRIPTION

FIG. 1 is a front perspective view of a side brush; FIG. 2 is a rear perspective view of the side brush of FIG. 1;

FIG. 3 is a front view of the side brush of FIG. 1;

FIG. 4 is a rear view of the side brush of FIG. 1;

FIG. 5 is a left view of the side brush of FIG. 1;

FIG. 6 is a right view of the side brush of FIG. 1;

FIG. 7 is a top view of the side brush of FIG. 1; and,

FIG. 8 is a bottom view of the side brush of FIG. 1.

The broken lines in the drawings represent various features or elements of the side brush that form no part of the claimed design.

1 Claim, 8 Drawing Sheets
